UNITED STATES PATENT OFFICE.

GEORGE HENRY WHEARY, OF RACINE, WISCONSIN.

GARMENT-HANGER FIXTURE.

1,216,384.

Specification of Letters Patent.

Patented Feb. 20, 1917.

Application filed October 24, 1914. Serial No. 868,409.

To all whom it may concern:

Be it known that I, GEORGE HENRY WHEARY, a citizen of the United States, and resident of Racine, in the county of Racine 5 and State of Wisconsin, have invented new and useful Improvements in Garment-Hanger Fixtures, of which the following is a description, reference being had to the accompanying drawings, which are a part of 10 this specification.

This invention relates to improvements in garment hanger fixtures.

It is of material benefit to the traveling public to be able to transfer garments from 15 their trunks to the closets in the hotels or other stopping places and it is also of advantage if the trunk hangers with the garments draped thereon can be taken from the trunk and supported in the closets as 20 considerable time is saved and the user is provided with the desired number of hangers.

Modern wardrobe trunks of the better class are provided with garment hangers which are slidably supported at their opposite ends upon tracks removably mounted 25 within the wardrobe section of the trunk. Garment hangers of this type are not adapted to be supported from the ordinary clothes hooks usually found in the closets of hotels 30 and other places so that other hangers have to be provided or the garments be hung on the ordinary hook.

It is one of the objects of the present invention to provide a garment hanger fixture 35 to which the modern removable garment hanger tracks and hangers may be supported therefrom.

A further object of the invention is to provide a garment hanger fixture having 40 portions which may be permanently fastened to a support, and which portions are adapted to support garments in the ordinary manner and to also hold garment hanger tracks transferred from trunks.

45 A further object of the invention is to provide a garment hanger fixture in which the removable portion of the fixture is locked to the permanently attached portions by the removable garment hanger tracks.

50 A further object of the invention is to provide a garment hanger fixture which is adapted to support garment hanger tracks of the extensible type.

A further object of the invention is to

provide a garment hanger fixture which is 55 of simple construction, is strong and durable and is well adapted for the purpose described.

With the above and other objects in view, the invention consists of the improved garment hanger fixture and its parts and combinations as set forth in the claims, and all equivalents thereof.

In the accompanying drawing in which the same reference characters indicate the 65 same parts in all of the views:

Figure 1 is a top view of the improved garment hanger fixture and removable tracks connected thereto shown attached to a support; parts of the tracks being broken 70 away to show other parts therebeneath and one of the tracks being in a position to be removed from the fixture;

Fig. 2 is a transverse sectional view thereof on a larger scale taken on line 2—2 of 75 Fig. 1;

Fig. 3 is a horizontal sectional view of the fixture taken on line 3—3 of Fig. 2; and

Fig. 4 is a sectional view of the fixture taken on line 4—4 of Fig. 1. 80

Referring to the drawing the numeral 8 indicates a support and 9 the improved garment hanger fixture mounted thereon. The fixture comprises bracket members 10 and track holding members 11 which are removably attached to the said brackets and to which the tracks 12 are removably connected. Each bracket member 10 is stamped from heavy sheet or plate metal and consists of a body portion 13 having a depending loop portion 14, an upper hook portion 15 and side ear portions 16. The ear portions 16 are perforated to receive screws 17 for attaching the member permanently to a support, and the upper portion 15 is bent 95 to form a clothes hook 18 adapted to support garments in the ordinary manner. The depending portion 14 is bent upwardly and over upon the body to form an elongated eyed or slotted part 19 extending transversely of the member and parallel to the face thereof. Rivets 20 serve to securely bind the upper part of the eyed portion to the body portion of the member to form a rigid structure. 100

Each track holding member 11 consists of an elongated piece of flat metal having its inner end portion bent at right angles to

form an inner attaching portion 21 and an outwardly projecting side portion 22. The right angled attaching portion is adapted to extend through and snugly fit into the 5 elongated eye 19 of the holding member.

In order to firmly brace the track holding member and connect it to the bracket an angular or L-shaped reinforcing holding member 23 is provided which is connected to the 10 inner side of the side portion 22 of the holding member adjacent to the attaching portion 21. The projecting bracing portion 24 of the reinforcing member is spaced from the attaching portion of the holding 15 member a sufficient distance to permit the outer part 19' of the eyed portion of the bracket to just pass between the said brace portion 24 and the attaching portion 21 and form a close engagement therewith and thus 20 firmly bracing the said holding member.

While only one of the fixtures is described in detail it is to be understood that they are ordinarily adapted for use in pairs in which a right and left form is used in spaced relation to support the tracks. It is also to be understood that one of the fixtures may be used for holding a number of clothes hangers of ordinary type.

The trunk tracks 12 adapted for use in 30 connection with these fixtures are formed of metal rods having annular recesses 25 extending around their inner ends and the recessed portions of said tracks on their lower sides are slabbed as indicated by the numeral 26 to permit the said recessed portions to enter the locking recesses 27 formed in the attaching portions 21 of the track holding members 11.

The lower portion 27' of each locking recess 27 is of circular form corresponding in 40 diameter to the diameter of the recessed portions of the tracks, while the upper or entrance portion 28 of each recess is of less width than the lower portion and corresponds in width to the transverse thickness 45 of the slabbed portions of the tracks. This construction permits the recessed and slabbed portions of the tracks to enter the recesses and by giving a quarter turn to the tracks to turn the slabbed portions of the tracks out of register with the entrance recesses, the tracks at their inner ends will be 50 securely locked to the attaching portions of the track holding members.

The outer side end portions of the tracks are provided with curved laterally-extending plates 29 having hook like end portions 30 which hook over the upper edge portions 31 55 of the side portions 22. These curved plates 60 project outwardly from the tracks in planes at right angles with relation to the planes of the faces of the slabbed portions of the tracks so that when the hooked portions of the plates are revolved to engage the upper edges of the side portions the rear end por-

tions of the tracks will be locked to the attaching portions of the track holders.

Each curved plate has mounted thereon a spring actuated bolt 32 which projects outwardly therefrom and extends into the locking openings 33 of the side portions of the track holders to lock the plates in holder engaging position. The plates are unlocked from the bands by pressing inwardly on the projecting ends 32' of the spring portions 75 of the bolts.

The outer end portions of the tracks are provided with hinged extensible tracks 34 which are adapted to swing horizontally outwardly and into longitudinal alignment 80 with the fixed tracks to which they are respectively connected to permit garment hangers 35 mounted on the fixed tracks to be slid outwardly and upon the extensible tracks so that garments carried by the hangers 85 may be easily removed or replaced. The outer end portions of the extensible tracks are arranged to overlap and interlock with each other when in closed position.

From the foregoing description it will be 90 seen that the track holder portions may be carried in a trunk and when the destination is reached the holder portions may be mounted in a closet provided with the bracket portions and the tracks and the garment hangers 95 from the trunk may be supported on the fixtures in the same manner as supported in the trunk thus permitting the use of the same tracks and hangers outside of the trunk.

It will also be seen that the brackets may also be used as ordinary clothes hooks and also that single tracks may be used to support garment hangers of the ordinary type.

What I claim as my invention is:

1. A garment hanger fixture, comprising 100 a bracket member adapted to be connected to a support, a track holder removably connected to said bracket, and a garment hanger track removably connected to the holder.

2. A garment hanger fixture, comprising 110 a bracket member adapted to be connected to a support, a track holder removably connected to said bracket, and a garment hanger track revolvably removably connected to said 115 holder.

3. A garment hanger fixture, comprising 120 a bracket member adapted to be connected to a support, a track holder laterally engaging said bracket, and a garment hanger track revolvably removably connected to said holder.

4. A garment hanger fixture, comprising 125 a bracket adapted to be connected to a support and having an elongated eyed portion, a track holder having an attaching portion which extends through the eye of the eyed portion, and a garment hanger track removably connected to the attaching portion and to another portion of the holding member.

5. A garment hanger fixture, comprising a bracket adapted to be connected to a support and having an elongated eyed portion and a garment hook portion, a track holder having an angularly projecting attaching portion which extends through the eye of the eyed portion, and a garment hanger track revolvably removably connected to the attaching portion of the holder and to another portion thereof. 10
6. A garment hanger fixture, comprising a bracket adapted to be connected to a support and having an elongated eyed portion and an upper garment hook portion, a track holder having an angularly projecting attaching portion which extends through the eye of the eyed portion, a reinforcing member forming part of the holder and engaging the outer face of the eyed portion of the bracket, and a garment hanger track removably connected to the attaching portion of the holder and to another portion thereof. 15
7. A garment hanger fixture, comprising a bracket adapted to be connected to a support and having an elongated lower eyed portion and an upper garment hook portion, a track holder having an angularly projecting attaching portion which extends through the eye of the eyed portion and is provided with a locking recess, and a garment hanger track having a recessed inner end portion which removably enters the locking recess of the holder and is provided with another portion which engages the outer end portion of the said holder. 20
8. A garment hanger fixture, comprising a bracket adapted to be connected to a support and having an elongated lower eyed portion and an upper garment hook portion, a track holder having an angularly projecting attaching portion which extends through the eye of the eyed portion and is provided with a locking recess, and a garment hanger track having a recessed inner end portion which removably enters the locking recess of the holder and is provided with a laterally projecting portion of hook-like form which hooks over the outer end portion of the said holder. 25
9. A garment hanger fixture, comprising a bracket adapted to be connected to a support and having an elongated lower eyed portion and an upper garment hook portion, a track holder having an angularly projecting attaching portion which extends through the eye of the eyed portion and is provided with a locking recess, a reinforcing member forming part of the holder and engaging the outer face of the eyed portion of the bracket, and a garment hanger track having a recessed inner end portion which removably enters the locking recess of the holder and is provided with another portion which engages the outer end portion of the said holder. 30
10. A garment hanger fixture, comprising a bracket adapted to be connected to a support and having an elongated lower eyed portion and an upper garment hook portion, a track holder having an angularly projecting attaching portion which extends through the eye of the eyed portion and is provided with a locking recess, a reinforcing member forming part of the holder and engaging the outer face of the eyed portion of the bracket, and a garment hanger track having a recessed inner end portion which removably enters the locking recess of the holder and is provided with a laterally projecting portion of hook-like form which hooks over the outer end portion of the said holder. 35
11. A garment hanger fixture, comprising a bracket having means for connecting it to a support and also having an elongated lower eyed portion and an upper garment hook portion, a track holder having an angularly projecting attaching portion which extends through the eye of the eyed portion and is provided with a locking recess, the lower portion of said recess being of greater width than the width of the entrance portion, and a garment hanger track having an annular recessed inner portion, the recessed portion of the track being of a transverse thickness in one direction corresponding approximately to the larger width of the holder recess and in another direction corresponding approximately to the less width of the entrance portion of said holder recess, said track recessed portion removably entering the holder recess, said track also provided with a laterally projecting hook portion which engages the outer end portion of the holder. 40
12. A garment hanger fixture, comprising a bracket having means for connecting it to a support and also having an elongated lower eyed portion and an upper garment hook portion, a track holder having an angularly projecting attaching portion which extends through the eye of the eyed portion and is provided with a locking recess, the lower portion of said recess being of greater width than the width of the entrance portion, a reinforcing member forming part of the holder and engaging the outer face of the eyed portion of the bracket, and a garment hanger track having an annular recessed inner portion, the recessed portion of the track being of a transverse thickness in one direction corresponding approximately to the larger width of the holder recess and in another direction corresponding approximately to the less width of the entrance portion of said holder recess, said track recessed portion removably entering the holder recess, said track also provided with a laterally projecting hook portion which engages the outer end portion of the holder. 45

13. A garment hanger fixture, comprising a pair of brackets adapted to be connected to a support in spaced relation, said brackets having elongated lower eyed portions and upper garment hook portions, track holders having angularly projecting attaching portions which extend toward each other through the eyes of the eyed portions, said attaching portions provided with locking recesses, and garment hanger tracks having recessed inner portions which removably enter the locking recesses and having their outer portions projecting outwardly from said attaching portions in parallel lines and the outer end portions of said tracks having laterally projecting hook plates which engage the outer end portions of the holder members.
14. A garment hanger fixture, comprising a pair of brackets adapted to be connected to a support in spaced relation, said brackets having elongated lower eyed portions and upper garment hook portions, track holders having angularly projecting attaching portions which extend toward each other through the eyes of the eyed portions, said attaching portions provided with locking recesses, garment hanger tracks having recessed inner portions which removably enter the locking recesses and having their outer portions projecting outwardly from said attaching portions in parallel lines, and the outer end portions of said tracks having laterally projecting hook plates which engage the outer end portions of the holder members.

members, and extensible tracks hinged to the outer ends of the first mentioned tracks.

15. A garment hanger fixture, comprising a pair of brackets adapted to be connected to a support in spaced relation, said brackets having elongated lower eyed portions and upper garment hook portions, track holders having angularly projecting attaching portions which extend toward each other through the eyes of the eyed portions, said attaching portions provided with locking recesses, reinforcing members forming part of the holders and having projecting portions which engage the outer face portions of the eyed portions of the brackets, and garment hanger tracks having recessed inner portions which removably enter the locking recesses and having their outer portions projecting outwardly from said attaching portions in parallel lines, and the outer end portions of said tracks having laterally projecting hook plates which engage the outer end portions of the holder members.

16. A garment hanger fixture, comprising a bracket member adapted to be connected to a support, a garment hanger track positioned adjacent thereto, and means for removably connecting the track in locked position to the bracket member.

In testimony whereof, I affix my signature, in presence of two witnesses.

GEORGE HENRY WHEARY.
